UNITED STATES PATENT OFFICE.

HARVEY B. CARLTON, OF ROCHESTER, NEW YORK, ASSIGNOR TO CARLTON MANUFACTURING COMPANY, OF ROCHESTER, NEW YORK, A CORPORATION OF NEW YORK.

PAY-ROLL COMPUTER.

SPECIFICATION forming part of Letters Patent No. 740,394, dated October 6, 1903.

Application filed February 28, 1903. Serial No. 145,532. (No model.)

To all whom it may concern:

Be it known that I, HARVEY B. CARLTON, a citizen of the United States, residing at Rochester, in the county of Monroe and State of New York, have invented new and useful Improvements in Pay-Roll Computers, of which the following is a specification.

My invention relates to a device employing a web movable across a sight-opening for displaying numbers or other characters or markings on the web, and has special reference to the manner of mounting and operating the rollers to which the ends of the web are attached.

15 I have illustrated my invention as embodied in a device designed to compute wages, and to this end have shown the web as provided with columns of numbers arranged in the manner hereinafter described to indicate amounts of salary due for different periods of time at a given rate per week or hour and the top of the casing provided with an index or scale of wages arranged for coöperation with the figures on the web. It will be apparent, 25 however, that the web may be employed for displaying characters other than figures and with or without the coöoperating scale and also that the figures on the web and casing may be arranged and adapted for purposes 30 other than that of computing wages—such, for example, as computing interest, computing the cost of articles, and the like.

The objects had in view are to mount the operating-rollers in a readily-detachable manner upon a base or support, to provide a novel means for retaining the rollers in position, to provide a novel manner of mounting and operating the gears for driving the rollers, and generally to provide a simple, economical, and 40 easily-operated device of the character indicated.

In order that my invention may be clearly understood, I have illustrated the same in the accompanying drawings, in which—

45 Figure 1 represents a part plan and part sectional plan view of a device constructed according to my invention. Fig. 2 is a sectional view taken on the line 2-2 of Fig. 1 designed to show the arrangement of gears and 50 the location of the rollers with respect to the

sight-openings or slots in the top of the casing. Fig. 3 is an end view of the device, the operating-gear and the intermediate gear being removed. Fig. 4 is a section on the line 4-4 of Fig. 1, taken between the ends of the 55 rollers and the retaining-plate and viewed in the direction indicated by the arrows. Fig. 5 is a perspective view of a removable bottom provided with supporting-brackets, all of the operating parts of the device being removed 60 therefrom. Fig. 6 is a detail perspective view of the plate for retaining the rollers in position. Fig. 7 is a similar view of the milled disk for operating the device, showing the operating-gear attached thereto; and Fig. 8 is 65 a side elevation of one of the rollers.

Referring now to the drawings, in which like reference-numerals designate corresponding parts throughout the several views, 1 indicates a casing, and 2 the base of the 70 device, which in practice operates as the bottom for the casing, being first in practice inserted in the casing to the proper height and then secured by means of screws 3 passed through the sides of the casing and secured 75 into the edges of said base. The said base has mounted thereon the entire operating mechanism of the apparatus, and this mechanism will now be described. Adjacent to each end of the base 2 is mounted a bracket 80 4, which comprises a single plate of material bent at right angles to itself to form a base or foot portion 5, by means of which the bracket is secured to the base by means of screws 6, and an upright portion 7, in which 85 are rotatably mounted the operating-rollers. To this end one of the brackets 4 is provided with apertures 8, adapted to receive journals 9, one of which is provided at one end of each roller. The other bracket 4 is provided near 90 opposite ends with slots 10, opening from the upper side of the bracket, said slots being directed or inclined outward in a downward direction.

11 indicates the rollers, each of which is 95 provided at the end opposite to that for the journal 9 with a journal 12, projecting a suitable distance beyond the end of the roller, and on the end of which is fixedly secured a small gear-wheel 13. The journals 12 are 100

adapted to be received and seat in the bottoms of the slots 10, so that the gears 13 will be located outside of the bracket 4. Secured to and projecting from the outer face of the bracket 4, provided with the slots 10, are two studs 14 15, respectively, each of which is inferiorly screw-threaded. On the stud 14 is rotatably mounted a gear 16, in mesh with the small gear-wheel 13 on one of the rollers. Said gear is held on its stud by means of a washer 17, placed against the outside thereof, and a screw 18, passed through said washer and engaging in the screw-threads of the stud. 19 indicates a large disk, having its periphery milled, as indicated at 20, fixedly secured to the inner side of which is an operating-gear 21. An aperture 22 passes through said disk and operating-gear, and said gear and disk are designed thereby to be mounted on the stud 15, so that the operating-gear 21 shall mesh with the gear 16 and the small gear-wheel on the other roller. The disk 19, with its operating-gear, is retained on the stud 15 by means of a washer and a screw in the manner described with reference to the gear 16. The gear 16, it will be seen, is merely an intermediate gear connecting the operating-gear 21 with one of the gears on one of the rollers. In assembling the parts of the apparatus the rollers are first placed in position in the brackets 4 in the manner described, after which the intermediate gear 16 and the combined disk and operating-gear 19 21 are inserted on their respective studs. The outward incline of the slots 10 tends to prevent any upward displacement of the rollers 11 in the operation of the device, as will be understood; but to further center these rollers and to hold their gears in fixed relation with the intermediate gear 16 and operating-gear 21, respectively, and prevent all binding and undue wear I employ a retaining-plate 25. (Shown in detail in Fig. 6.) The plate 25 is of substantially the same length and height as the bracket 4 and is provided near each end with an enlarged recess 26, opening from the bottom. Near the top of the plate and at each end are provided two outwardly-projecting tongues 27 28, respectively, which are formed by cutting the metal at two places and then bending the intermediate portion of the metal outward. The bracket 4, containing the slots 10, is provided near its top and at each side with a recess 29 30, respectively; the recess 29 being longer than the recess 30. In placing the plate in position it is inserted between the ends of the rollers and the bracket 4, the recesses 26 passing over the respective journals 12 of the rollers. As shown in Fig. 4, the recesses 26 are of much greater width than said journals, so that the plate 25 may be moved to one side or the other. The plate having been placed in position in the manner just described it is moved to one side and pressed down at one end, so that the tongue 27 may be inserted in the recess 29. It is then moved to one side

in the opposite direction, bringing the tongue 27 substantially to the end of the recess 29, and then the opposite end of the plate is 70 pressed down to bring the tongue 28 opposite the recess 30, after which the plate is moved laterally to cause said tongue 28 to enter the recess 30. Such movement of the plate, however, will not cause the tongue 27 to be 75 moved out of the recess 29 owing to the difference in length of the recesses 29 and 30. When thus placed in position, the tops of the recesses 26 in said plate will engage the journals 12 and prevent them from rising, while 80 slots 10 will prevent movement laterally of said journals.

31 indicates the web, opposite ends of which are secured to the respective rollers 11 and wound thereon in such manner that one roller 85 will display one side of the web, while the other roller will display the opposite or under side. In other words, the web passes from the under side of one roller to the upper side of the other. 90

The rollers and the operating mechanism having been mounted on the base 2 in the manner described, said base may now be inserted in the casing 1 and is screwed in position by the screws 3. The casing 1 is provided near one end with a transverse slot 32, through which the winding-disk 19 may protrude. The said casing is also provided on its upper side with an index or scale, which may be made from cardboard or any other suitable material and is indicated generally by the numeral 33, said scale or index being provided with two longitudinal slots or sight-openings 34 35, respectively, which extend immediately over and along the rollers 11, 105 containing the web 31. The sight-openings 34 35 correspond and register with similar openings made in the top of the casing, as will be understood, the scale-card or index being pasted or otherwise secured to the top 110 of the casing. The said scale 33 will preferably be covered with some transparent material, such as glass or celluloid 36.

In the preferred embodiment of the invention, as illustrated herein, I arrange in a column adjacent to one edge—say the left-hand edge of each sight-opening or slot 34 35—a column of figures which indicate different weekly salaries, such column being indicated by 37, while to the left of this column is arranged a second column 38, indicating the rate perhour of the wages. To the right of each sight-opening are arranged three columns of figures 39, 40, and 41, indicating, respectively, the rate of salary for one-fourth, 120 one-half, and three-fourths of an hour. In the center of the scale is provided a space 42, which is utilized for designating in a suitable manner these various columns. Thus in this space the column 37 is designated "Rate 130 per week," this designation applying to the numbers above and below the space in this column. The column 38 is designated by the words "Rate per hour." The columns 39, 40,

and 41 are indicated in this space by the characters " $\frac{1}{4}$," " $\frac{1}{2}$," and " $\frac{3}{4}$," respectively. The web 31 is provided with a central space 43, with columns of numbers extending above and below it, and is provided at intervals with a series of numbers made considerably larger than the other numbers on the web, said series of large numbers extending longitudinally of the web and each number being located in the space 43 in the line of a given column of numbers on the web. The web 31 is correspondingly numbered on both sides, and in operation two columns of numbers on the web may be made to appear simultaneously at each of the openings 34 35, and each column thus made to appear will disclose the same number in the central space 43. In the arrangement of the scale and of the two columns of figures which are simultaneously disclosed by the web the column of figures on the web at the right of the device and the columns of figures arranged with respect to the aperture through which said column is disclosed are continuations of a like arrangement of numbers at the left of the device—that is to say, the combined arrangement of numbers at the right begins at the top where the combined arrangement of numbers left off at the bottom of the column at the left.

The principle is precisely the same as though only one roller were employed; but two rollers displaying two columns of numbers are employed for the purpose of affording greater amplitude of computation. In the same manner four or more rollers could be employed to display a corresponding number of columns of figures. The numbers on the web and scale are based on a day of ten hours, and a single illustration will suffice to show the use of the device.

Supposing it be desired to find the amount due an employee who has worked fifty-seven hours and receives a salary of fifteen dollars per week for ten hours a day. To ascertain this, the disk 19 is turned until the number "57" in the space 43 in the center of the web appears at the sight-openings 34 35. The operator then runs his eye down the column of numbers 37, which contains numbers indicating different weekly salaries, until "15.00" is reached. Opposite "15.00" on the column of numbers on the web will be displayed the numbers "14.25," which will indicate the amount due the workman. If the employee had worked fifty-seven and one-fourth hours, then the operator would refer to the first column to the right, indicated by "39," and opposite "14.25" he would find "6," which amount would be added to "14.25." If the time worked was fifty-seven and one-half hours, he would refer to the column 40, and opposite "14.25" he would find "13," which amount would be added to the "14.25." If the time worked was fifty-seven and three-fourths hours, he would refer to the column 41, and opposite "14.25" would find "19," which amount would be added to "14.25,"

thus giving the total amount due for fifty-seven and three-fourths hours' work. The large numbers at the center of the web indicate the total number of hours or work. If the salary is based on a rate per hour, then the operator would simply refer to the column 38 to ascertain the salary due in place of the column 37—that is to say, using the same numbers as in the above illustration. If an employee had worked fifty-seven hours and received twenty-five cents an hour for his work, the amount shown to be due is "14.25." As stated, however, other arrangement of numbers may be employed, and I have described and illustrated an arrangement with which my invention was particularly designed to be operated.

It will be noted that the size of the rollers 85 11 is such as to bring the web into close proximity to the openings 34 35 in the top of the casing without the use of any other form of guide or supporting device.

Having thus fully described my invention, what I claim as new, and desire to secure by Letters Patent, is—

1. In a device of the character described, in combination with the casing having a sight-opening, a base, brackets mounted at opposite ends of said base, one of said brackets having downwardly and outwardly inclined slots, rollers having at opposite ends journals mounted in said brackets, the journals at one end being inserted in said slots, removable means for holding said journals in fixed positions in said slots, and a web secured at its ends to said rollers and movable thereby across and in proximity to said opening.

2. In a device of the character described in combination with the casing having a sight-opening, a base, brackets mounted on said base, one of said brackets having open-ended slots, rollers having at opposite ends journals mounted in said brackets, the journals at one end being inserted in said slots, a plate slidably interlocked with the bracket having the slots, and provided with recesses adapted to embrace the journals inserted in said slots, the tops of said recesses being adapted to engage said journals and hold them in place in their slots, and a web secured at its ends to said rollers and movable thereby across and in proximity to said opening.

3. In a device of the character described, in combination with the casing having a sight-opening, a base, brackets mounted near opposite ends of said base, one of said brackets having slots and being provided on opposite sides with recesses of different lengths, a plate provided with enlarged recesses and having outwardly extending tongues and adapted to have its recesses inserted over said journals in a manner to have the tops of said recesses engage the journals, and movable laterally in both directions to bring its tongues respectively into engagement with first the longer and then the shorter of the recesses in said bracket.

4. In a device of the character described, in combination with the casing having a sight-opening, a base, brackets mounted near opposite ends of said base, one of said brackets having slots, rollers having at opposite ends journals mounted in said brackets, the journals at one end being inserted in said slots and having on their outer ends a fixed gear, means for holding said journals in their slots, 5 studs on said last-named bracket, operating-gear mounted on one of said studs and meshing with the gear on one of said journals, an

operating-disk secured to said operating-gear adapted to project through a slot formed in said casing, and a web secured at its ends to 15 said rollers and movable thereby across and in proximity to said openings.

In testimony whereof I have hereunto set my hand in presence of two subscribing witnesses.

HARVEY B. CARLTON.
